UNITED STATES PATENT OFFICE

104,044

DESIGN FOR A WATCHCASE

David Ornstein, New York, N. Y., assignor to Louis
Watch Co. Inc., New York, N. Y.

Application March 19, 1936, Serial No. 61,699

Term of patent 7 years

To all whom it may concern:

Be it known that I, David Ornstein, a citizen of the United States, residing at 1315 Ftley Avenue, county of Bronx, city and State of New York, have invented a new, original, and ornamental Design for Watchcases, of which the following is a specification, reference being had to the accompanying drawing, forming part thereof.

Fig. 1 is a face view of a watchcase, showing my new design; and

Fig. 2 is a side elevation when viewed from the right of Fig. 1.

I claim:

The ornamental design for a watchcase, as shown and described.

DAVID ORNSTEIN.
